UNITED STATES PATENT OFFICE.

LAWRENCE B. GRAY, OF BOSTON, MASSACHUSETTS.

DESIGN FOR AN INKSTAND.

SPECIFICATION forming part of Design No. 13,996, dated June 19, 1883.

Application filed March 2, 1883. Term of patent 14 years.

To all whom it may concern:

Be it known that I, LAWRENCE B. GRAY, of Boston, in the county of Suffolk and State of Massachusetts, have invented and produced 5 a new and original Design for Inkstands, of which the following is a specification, reference being had to the accompanying drawing, forming part thereof.

The figure represents a perspective view of 10 my newly-designed inkstand.

The leading feature of my design consists in the shape or outline, and particularly in the main elevated top portion, wherein A is a rectangular projection having a corrugated upper 15 surface, B, and C is a circular cavity, and E is a transverse semicircular groove, and H an elevated circular neck having an internal open-

ing communicating with the hollow interior of the main body portion L, from which it projects about one-half of its exterior diameter, 20 and is formed at a right angle to the bottom of the main portion or body.

Having thus described my design, what I claim is—

A design for an inkstand, consisting of the 25 main hollow body portion L, having a hollow circular elevated neck, H, a transverse semicircular groove, E, a circular cavity, C, and a rectangular projection, A, having a corrugated upper surface, B.

LAWRENCE B. GRAY.
